(57) **CLAIM**

We claim the ornamental design for a diving board, as shown and described.

DESCRIPTION

FIG. 1 is a top isometric view of a diving board in accordance with a first embodiment.

FIG. 2 is a bottom isometric view of the diving board of FIG. 1.

FIG. 3 is a top plan view of the diving board of FIG. 1.

FIG. 4 is a bottom plan view of the diving board of FIG. 1.

FIG. 5 is a side elevation view of the diving board of FIG. 1.

FIG. 6 is a front elevation view of the diving board of FIG. 1.

FIG. 7 is a rear elevation view of the diving board of FIG. 1.

FIG. 8 is a top isometric view of a diving board in accordance with a second embodiment.

FIG. 9 is a bottom isometric view of the diving board of FIG. 8.

FIG. 10 is a top plan view of the diving board of FIG. 8.

FIG. 11 is a bottom plan view of the diving board of FIG. 8.

FIG. 12 is a side elevation view of the diving board of FIG. 8.

FIG. 13 is a front elevation view of the diving board of FIG. 8.

FIG. 14 is a rear elevation view of the diving board of FIG. 8.

FIG. 15 is a top isometric view of a diving board in accordance with a third embodiment.

FIG. 16 is a bottom isometric view of the diving board of FIG. 15.

FIG. 17 is a top plan view of the diving board of FIG. 15.

FIG. 18 is a bottom plan view of the diving board of FIG. 15.

FIG. 19 is a side elevation view of the diving board of FIG. 15.

FIG. 20 is a front elevation view of the diving board of FIG. 15.

FIG. 21 is a rear elevation view of the diving board of FIG. 15.

FIG. 22 is a top isometric view of a diving board in accordance with a fourth embodiment.

FIG. 23 is a bottom isometric view of the diving board of FIG. 22.

(Continued)

FIG. 24 is a top plan view of the diving board of FIG. 22. FIG. 25 is a bottom plan view of the diving board of FIG. 22. FIG. 26 is a side elevation view of the diving board of FIG. 22. FIG. 27 is a front elevation view of the diving board of FIG. 22. FIG. 28 is a rear elevation view of the diving board of FIG. 22. FIG. 29 is a top isometric view of a diving board in accordance with a fifth embodiment. FIG. 30 is a bottom isometric view of the diving board of FIG. 29. FIG. 31 is a top plan view of the diving board of FIG. 29. FIG. 32 is a bottom plan view of the diving board of FIG. 29. FIG. 33 is a side elevation view of the diving board of FIG. 29. FIG. 34 is a front elevation view of the diving board of FIG. 29. FIG. 35 is a rear elevation view of the diving board of FIG. 29. FIG. 36 is a top isometric view of a diving board in accordance with a sixth embodiment. FIG. 37 is a bottom isometric view of the diving board of FIG. 36. FIG. 38 is a top plan view of the diving board of FIG. 36. FIG. 39 is a bottom plan view of the diving board of FIG. 36. FIG. 40 is a side elevation view of the diving board of FIG. 36. FIG. 41 is a front elevation view of the diving board of FIG. 36; and, FIG. 42 is a rear elevation view of the diving board of FIG. 36. The stippling depicts textured surface that forms part of the claimed design. The broken lines in the drawings depict unclaimed portions of the diving board only and form no part of the claimed design.
